[57] CLAIM

The ornamental design for a cup shaped sole, as shown and described.

DESCRIPTION

FIG. 1 is a bottom plan view of the cup shaped sole showing our new design;

FIG. 2 is a side elevational view of one side of a cup shape sole shown in FIG. 1;

FIG. 3 is a side elevational view of the other side of the cup shaped sole shown in FIG. 1;

FIG. 4 is a front elevational view of the cup shaped sole shown in FIG. 1;

FIG. 5 is a rear elevational view of the cup shaped sole shown in FIG. 1;

FIG. 6 is a cross-sectional view as shown in section 6—6 of FIG. 1;

FIG. 7 is a cross-sectional view as shown in section 7—7 of FIG. 1;

FIG. 8 is a cross-sectional view as shown in section 8—8 of FIG. 1;

FIG. 9 is a cross-sectional view as shown in section 9—9 of FIG. 2;

The broken line showing of a shoe upper is for illustrative purposes only and forms no part of the claimed design.
